HOLDER

William A. Warnock, Spartanburg, S.C., assignor to
Whitin Machine Works, Whitinsville, Mass., a corporation of Massachusetts
Filed Oct. 5, 1962, Ser. No. 228,663
9 Claims. (Cl. 242—130.2)

This invention relates in general to holders and more particularly to rotatable bobbin holders for spinning machines.

Most types of bobbin holders, heretofore used for suspending bobbins in the creel of a spinning frame, have many parts including spring-actuated fingers made to engage the usual shoulder at the upper end of the bobbins. One of the main objects of the present invention is, therefore, to provide a bobbin holder of the type described which is economical to manufacture and which requires a minimum number of parts. The present invention provides a simple design which is not only economical to manufacture but is also efficient in operation.

The invention includes a rotatable holder comprising an overhead support to which a body portion is rotatably mounted. The body portion is generally elongated and has a channel passing transversely through its center. The lower portion of a movable slide positioned within this channel protrudes when the slide is positioned at its lowest point in the channel. This protruding portion supports at least in part the weight of a rotatable bobbin which can be mounted about the suspended body portion. This design includes limiting means for fixing the lowest position for the movable slide and provides a method for retracting the protruding portion of the movable slide when the rotatable bobbin or other object is being engaged or disengaged.

In addition many other uses are envisioned for this suspended rotatable holder in fields other than in the textile industry. Other objects and a fuller understanding of this invention may be had by referring to the following description and claims taken in conjunction with the accompanying drawings in which:

FIGURE 1 is a slightly enlarged side elevation of the new bobbin holder;

FIGURE 2 is a vertical cross-section of the holder shown in FIGURE 1;

FIGURE 3 is a sectional plan view taken along line 3—3 in FIG. 1; and

FIGURE 4 is an elevational view of the movable bobbin holding member or slide.

Referring to the drawing, the bobbin holder comprises a body 10 having an upper portion 11, a flange 12 and a lower portion 13. The upper portion 11, as shown in FIGURE 2, is recessed to receive a ball-bearing 18 and a spherical head 15 of a stud 14, these parts being united by spinning or crimping the upper end 17 of the body over the outer race.

A dust cover 20 is mounted on the stud 14 against a shoulder 21 and the cover is provided with a pin 22 upon which pivots a brake member 23. The upper end 16 of the stud 14 is threaded to receive a nut 24 which nut secures the dust cover and the stud to a slotted creel bar 25. When these parts are so assembled, the body 10 is free to rotate about the stud 14.

The bottom of the stud 14 has a tongue 26 and the bottom of the recess in the body 10 is provided with a groove 27. By raising the body so that the tongue enters the groove, the body can be used as a wrench to screw the stud into or unscrew it from the nut 24. In this manner the edges of creel bar 25 and cover 20 may be clamped tightly between shoulder 21 and nut 24, thereby rigidly fixing stud 14 in position. The anti-fric-

2

tion mounting, dust cover, brake and creel member are of conventional type.

The body 10 is molded from a plastic material, such as polyethylene, and its lower portion 13 is preferably of the shape shown in FIGURE 3, having its radial extremities defining a circle slightly less than the upper bore of a bobbin 29 on which is wound a roving package (not shown). As shown in FIGURES 1 and 2, the axis of the lower portion 13 is offset, preferably about three degrees (3°), with respect to the vertical axis of the upper portion 11.

The body 10 is provided with an inclined slideway 30 as shown in FIGS. 2 and 3, in which is located a freely movable slide 31. Normally, this slide falls by its own weight until the surface 32 engages the edge 33 of the slideway 30. This is the lowest position which slide 31 occupies and its lower end 34 projects outwardly from the body 10, as shown in FIG. 1.

When attaching a bobbin to the holder, segment 39 of the top inner edge 35 of the bobbin will initially engage the surface 36 of the slide so that the latter is moved upward to retract its lower end into the slot or slideway 30. The bobbin is then made to drop slowly allowing the slide to return to its lowest position, whereupon the lower edge segment 37 of the bobbin 29 will be engaged by the surface 38 of the slide, as shown in FIG. 1. In addition to this bobbin-slide engagement, the lower body portion engages bobbin 29 only at segment 39 of upper edge 35 and at lower edge segment 40 of the upper bore 41. This is due to the approximate three degree (3°) inclination or offset of this lower portion of the body. The bobbin 29, however, is consequently suspended with its axis substantially parallel to the axis of the upper body portion 11, as shown in FIG. 1.

To remove the bobbin from the holder, the operator raises the bobbin to lift the slide 31 into position, as shown in FIG. 2. Here the bobbin 29 moves further along the opposite side of the top inner edge 35 than during engagement, subsequently engaging the surface 32 of slide 31 and continuing to displace the slide upwardly until stopped by flange 12. The operator then lowers the bobbin quickly, thereby preventing the surface 38 of the slide 31 from getting under the lower edge segment 37.

This invention thus provides a rotatable bobbin holder composed basically of two parts suspended from a ball-bearing support. This simple and functional design thus provides the industry with a durable, inexpensive, easily replaceable bobbin holder which operates efficiently as a spinning bobbin support and which may be easily engaged or disengaged from a creel frame in virtually a matter of seconds.

Although the invention has been described with a certain degree of particularity, it is understood that the present disclosure has been made only by way of example and that numerous changes in the details of construction and the combination and arrangement of parts may be resorted to without departing from the spirit and scope of the invention as hereafter claimed.

For example, other embodiments are envisioned wherein the bracing or stopping surface which determines the lowest limit for the slide 31 may be located either within the inclined channel 30 or adjacent the lower opening of inclined channel and is, therefore, not strictly a function of surface 32. It is to be understood that other detail changes in design, such as replacing the upper cylindrical body portion with a rib web construction similar to the lower body portion and the construction of a non-rotatable holder, are also contemplated. These and other numerous changes in construction details are to be considered within the scope of this invention.

I claim:

1. A rotatable holder comprising
an overhead support,
a suspended ball-bearing support attached to the lower
side of said overhead support,
an upper body portion having a longitudinal axis
mounted and rotatable around said suspended ball-
bearing support,
a lower body portion connected to said upper body portion
and having a longitudinal axis inclined with re-
spect to said longitudinal axis of said upper body
portion and having an inclined channel passing
through said lower body portion, and
a slide movable within said inclined channel having a
first protruding surface on the lower side of said
slide for supporting at least in part a rotatable object
mounted about said lower body portion when said
slide is positioned at the lowest position in said in-
clined channel, and having a second protruding sur-
face on the lower side of said slide for initially re-
tracting said protruding surfaces on the lower side
at said slide, and having a third protruding surface
on the upper portion of said slide for determining
the lowest position of said slide and for subsequently
retracting said protruding surfaces on the lower side
of said slide when disengaging said rotatable object.
2. A rotatable holder comprising
supporting means having ends forming a slot,
nut means within said slot in said supporting means,
a stud having a threaded end receivable in said nut and
having a second end including a tongue positioned on
said second end, and
body means rotatably mounted about said second end
of said stud having a groove in its upper surface for
receiving said tongue when said body means is pushed
against said stud whereby said threaded end of said
stud may be screwed into and out of said nut means.
3. A bobbin holder comprising
supporting means,
body means mounted upon said supporting means for
substantially vertical rotation, said body means hav-
ing a channel passing therethrough that is inclined
with respect to the longitudinal axis of said body
means, and
movable means within said channel which falls by its
own weight to its lowest position for engaging and
supporting a bobbin.
4. A holder comprising,
body means having a channel passing therethrough,
movable means within said channel which falls by its
own weight to its lowest position, having a protruding
portion for supporting at least in part an object
mounted about said body means when said movable
means is located at its lowest position, and
means for retracting said protruding portion of said
movable means to a position within said channel
spaced from said object mounted about said body
means when engaging and disengaging said object.
5. A holder as defined in claim 4 further comprising
limiting means attached to said body means for determin-
ing said lowest position of said movable means.
6. A holder as defined in claim 4 further comprising
means for guiding the fall and upward movement of said
movable means through a non-vertical path.
7. A holder comprising
supporting means,
body means mounted upon said supporting means hav-
ing a channel passing therethrough,

movable means within said channel which falls by its
own weight to its lowest position, having a protrud-
ing portion for supporting at least in part an object
mounted about said body means when said movable
means is located at its lowest position, and
means for retracting said protruding portion of said
movable means when engaging and disengaging said
object which comprises

initial retracting means attached to the lower portion
of said movable means for moving the protruding
portion of said movable means to an intermediate
position within said channel when engaging an ob-
ject on said holder, and

subsequent retracting means attached to the upper por-
tion of said movable means for moving the protrud-
ing portion of said movable means to its highest posi-
tion within said channel when disengaging an object
from around said body means of said holder.

8. A holder comprising
supporting means,
body means mounted upon said supporting means hav-
ing a channel passing therethrough, and
movable means within said channel which falls by its
own weight to its lowest position, having a protruding
portion for supporting at least in part an object
mounted about said body means when said movable
means is located at its lowest position, said movable
means having upper extending means for determin-
ing the lowest position of said movable means and for
moving said projecting portion of said movable
means to approximately its highest position within
said channel whereby an object mounted about said
body portion of said holder may be disengaged by
quickly moving the object downwardly from around
the body of said holder before said movable means
falls by its own weight to its lowest position.

9. A holder comprising
supporting means,
body means mounted upon said supporting means hav-
ing a channel passing therethrough, and
movable means within said channel which falls by its
own weight to its lowest position, having a protrud-
ing portion for supporting at least in part an object
mounted about said body means when said movable
means is located at its lowest position, said movable
means having lower extending means for moving
said movable means to an intermediate position within
said channel when engaging an object mounted
about said body portion, whereby a mountable object
may be moved to a point above the protruding por-
tion of said movable means when said movable
means is in its intermediate position and may be en-
gaged on said holder when said movable means falls
by its own weight to its lowest position.
